AMERICAN HARD RUBBER COMPANY, OF NEW YORK, N. Y., A CORPORATION OF
NEW YORK

FRAME FOR REFRIGERATOR DOORS

Application filed October 20, 1931. Serial No. 569,934.

This invention relates to the construction of frames for refrigerator doors of the display or show case type, or to other refrigerator parts such as lids, sashes or stiles. The 5 object of the invention is to provide a sturdy non-warping frame construction for such refrigerator parts, which frame structure will afford the greatest possible degree of sanitation, avoiding the cracks or joints usually 10 found in such structures wherein moisture may penetrate and create warping of the frame structure, or afford a place for the lodgement of food particles and the like which tend to create odors and which result 15 in an insanitary structure.

The objects of the invention are attained by utilizing a seamless, non-warping moulded hard-rubber frame casing for the frame structure wherein the formation of joints or 20 cracks is avoided and an entirely sanitary structure is provided. Such casing, in combination with associated novel constructional features hereinafter described, produces a smooth, neat frame of clean-cut appearance 25 and sturdiness.

The preferred embodiments of our invention are shown in the accompanying drawing, wherein Fig. 1 is a front elevation, partly in section, of a refrigerator door or 30 panel made in accordance with this invention; Fig. 2 is a sectional view on the line 2—2 of Fig. 1, looking in the direction of the arrows; Fig. 3 is a sectional view on the line 3—3 of Fig. 1, looking in the direction 35 of the arrows; Fig. 4 is an enlarged sectional view through the frame; and Fig. 5 is a front elevation, partly in section of a modified structure.

In the embodiment of the invention disclosed in Figs. 1 to 4 inclusive, 6 indicates the frame casing which may be of any desired shape to suit the particular use to which it is to be put. In hereafter referring to said frame as a "door frame", we 45 wish to be understood as meaning also, any fixed or movable frame structure forming part of a refrigerator, or a lid for an ice cream cabinet or any similar structure.

The frame casing shown at 6 consists of 50 a moulded structure of hard-rubber which

extends over and wholly encloses a filler or inner frame 7 that conforms to the shape of the casing and is preferably composed of solid wood, laminated wood, plywood, compressed wood, cork, fibre or other like structure of non-warping characteristics. Three 55 of the sides of the frame casing, namely, the outer edge 8, and the inner and outer faces 9 and 10, are of hard, impenetrable rubber, whereas the inner edge 11 of the frame, while preferably moulded as an integral portion of the frame casing, is of a softer texture of rubber and is readily penetrable by nails or similar fastening elements. The longitudinal side edges of the hard rubber frame casing 6 are longitudinally grooved, as at 12, to fit over and slide on rails on the refrigerator. These grooves 12, being suitably lubricated with a graphite compound or similar lubricant will permit the door to 70 slide easily with a minimum amount of friction on the rails without the use of rollers or bearings.

The frame, thus composed of the inner laminated wood filler 7 and the outer moulded 75 hard rubber casing 6, receives and holds several spaced glass panels or panes 13 and 14. These glass panels or panes are held in the frame in spaced relationship to provide an air-space 15 between them to aid in providing the maximum of heat insulation. The edges of the glass panels 13 and 14 rest against the softer rubber wall 11 of the frame casing and said panels are held in place in the frame by means of strips 16 and 17. The strip 16 is a spacing member and holds the two glass panels in their separated position and also acts to hold the outer glass panel 13 in the frame by holding it against a shoulder 18 integrally formed on the frame casing 6. Said strip 16 is secured in place by means of nails 19 or similar fastening elements, which are driven through said strip and through the penetrable rubber wall 11 provided on the frame casing 6. These nails readily penetrate the laminated wooden frame or filler 7 and are firmly anchored therein, although being readily manually removable for the replacement of a broken glass panel.

Similarly, the strip 17 holds the inner glass panel 14 in place, this strip 17 being secured in position by nails 20 which penetrate the wall 11 and enter into the wooden 5 filler.

While it is herein stated that the inner wooden frame or filler 7 may be shaped to conform to and wholly fill the inside of the hard-rubber casing 6, it is also possible to 10 provide a frame structure wherein such a continuous reinforcement of the hard-rubber frame casing by the wooden frame is unnecessary. In such a case, it may be found desirable to provide spaced reinforcing 15 blocks 21 located at intervals within the hollow hard-rubber frame casing as disclosed in Fig. 5. It will be there seen that the moulded hard-rubber casing is provided internally with numerous spaced blocks 21 20 which may be of laminated construction or solid wood. It will, of course, be understood that the frame casing may be internally reinforced by such laminated or other wooden blocks wherever required, either for 25 the reception of the nails used in attaching the strips 17 and 18, or to permit the secure fastening of a door handle, hinges, or the like, on the door.

The frame provided, being of seamless, 30 non-warping construction, is very sturdy and provides a maximum of heat insulation at a minimum of construction cost.

While we have shown our improved frame used in conjunction with glass panels, it 35 will be understood that such a frame structure can well form part of a solid door having no glass panels. It is also possible to utilize some moldable substance other than hard rubber as an outer covering, as will be 40 clearly understood by those skilled in this art.

What we claim is:—

1. A frame for refrigerator doors and the like having a hollow frame-casing provided with several walls composed of hard 45 rubber and having a wall of penetrable rubber, a penetrable filler located within the frame-casing and enclosed thereby, a panel held in the frame-casing with its edge located adjacent to the penetrable wall, a 50 strip for holding said panel in position, said strip being secured in place by a securing member passing through the strip and through the penetrable wall of the frame- 55 casing and entering into the filler.

2. A frame for refrigerator doors and the like having a laminated wood base enclosed by a hard-rubber covering, one of the walls of said covering being softer than the other walls thereof and being penetrable by 70 nails or like fastening elements, panels held in the frame, strips for holding said panels in place, and securing members for fastening said strips in position, said securing members extending through the penetrable 75 wall of the covering and projecting into the laminated wood base.

3. A frame portion for refrigerators consisting of a casing having several of its walls composed of a molded material, said casing holding panels, a penetrable filler within 80 said casing, and a wall of molded material formed on said casing and penetrable by fastening elements, said wall being disposed about the edges of the panels.

4. A frame portion for refrigerators consisting of a casing receiving and holding spaced panels, sections of laminated wood disposed within and confined by the casing, 90 said casing having several of its walls composed of hard-rubber and also having an inner wall composed of a softer rubber penetrable to nails or similar fastening elements, and means for retaining the panels within the frame comprising strips held in space by 95 nails passing through the strips and penetrating the penetrable wall and entering into the laminated wood sections.

5. A frame for refrigerators comprising a casing for receiving panels, said casing having several wall portions of moulded hard 100 rubber and having a softer wall portion against which the edges of said panels rest, said softer wall portion being formed integral with the casing and being capable of penetration by nails or like elements.

6. A refrigerator door structure having a wooden frame, a casing moulded over and wholly enclosing said frame, some of the walls of said casing being composed of hard-rubber and another wall of said casing being penetrable by nails.

7. A frame for refrigerator doors having a hollow hard-rubber casing provided with one relatively soft and penetrable wall, 11 and spaced sections of a penetrable filler located within and enclosed by the casing.

KENNETH J. DURANT.
